CLAIM

The ornamental design for a game board, as shown and described.

DESCRIPTION

FIG. 1 is an environmental perspective view of a game board showing my new design; and,

FIG. 2 is a top plan view thereof.

The broken line showing of the game pieces, die, and cards in FIGS. 1 and 2 is for illustrative purposes only and forms no part of the claimed design.

1 Claim, 2 Drawing Sheets

FIG. 1

FIG. 2
